(57) **CLAIM**

I Claim the ornamental design for a sleeping bag, substantially as shown and described.

DESCRIPTION

FIG. 1 is a front side elevational view of a sleeping bag showing my new design;

FIG. 2 is a rear elevational view thereof;

FIG. 3 is a front side elevational view shown in an open configuration thereof;

FIG. 4 is a right side elevational view of FIG. 1 thereof;

FIG. 5 is a front side elevational view shown in an alternate configuration of a sleeping bag showing my new design.

FIG. 6 is a top plan view thereof;

FIG. 7 is a left side elevational view thereof;

FIG. 8 is a rear elevational view thereof;

FIG. 9 is a bottom plan view thereof;

FIG. 10 is a right side elevational view thereof; and,

FIG. 11 is a left side elevational view thereof.

The small dash lines in FIGS. 1-4 represent stitching and are part of the claimed design.

The broken lines showing a handle, straps and child in FIGS. 5, 7, 8, and 11 of the sleeping bag are for the purpose of illustrating environment, and form no part of the claimed design.
